UNITED STATES PATENT OFFICE.

WILLIAM H. SOMMER, OF PEORIA, ILLINOIS, ASSIGNOR TO KEYSTONE STEEL & WIRE COMPANY, OF BARTONVILLE, ILLINOIS, A CORPORATION OF ILLINOIS.

FARM AND POULTRY FENCE.

Substitute for application Serial No. 521,534, filed December 10, 1921. This application filed May 10, 1923. Serial No. 638,150.

To all whom it may concern:

Be it known that I, WILLIAM H. SOMMER, a citizen of the United States, residing at Peoria, in the county of Peoria and State of Illinois, have invented new and useful Improvements in Farm and Poultry Fences, of which the following is a specification.

This invention has reference to fences and relates particularly to that type of fencing 10 which is used to enclose farm lands and poultry yards.

The invention relates further to fencing of the all-wire type and is preferably woven with open square meshes, formed by the 15 joining of vertical stay wires with longitudinal selvage and intermediate strand wires.

The invention herein contemplates the use of stay wires formed of short sections, the meeting ends of which are intercoiled around 20 the intermediate strand wires which they intersect, with the terminals of the upper and lower stay sections coiled or wrapped around the selvage or marginal wires.

Fencing of the general type described is 25 not new but embodies certain objectionable features, which the present invention is aimed to and does overcome. The objection referred to is the slippage of the strand wires in the coils of the stay sections, as the fence fabric or netting is stretched when 30 erecting the same. The reason for this is, that the strand wires upon which the ends of the stay sections are wrapped, are without bends at the points of intersections of the 35 stay sections therewith, and the fact that the wire used for the stay sections is never dead-soft annealed, and as soon as the intercoiling of the ends of the stay sections is completed, the coils naturally open slightly, 40 which permits a comparatively free movement of the strand wires within the coils of the stay sections, which will not only result in a spreading of the meshes which it is desired to keep uniform, but permits the slipping 45 page of the strand wires, which results in an irregular fabric and makes the stretching of the fabric very difficult, because to stretch properly there should be a firm gripping of the stay wires upon the strand wires, 50 so that the stretching may be uniform.

The principal object of the invention, therefore, is in providing the strand wires at the points of intersection of the stay wires

therewith with reverse bends, and it is on this portion of the strand wires and between 55 such bends that the stay sections are coiled. This construction will prevent the slippage of the strand wires in the coils of the stay sections, because any slippage would necessarily tend to bend the stay wires, and this 60 is prevented by the formation of the bends in the strands and the coiling of the stay wires therebetween, which places such coils at an oblique angle to the perpendicular line 65 of the bodies of the stay.

That the invention may be more fully understood, reference is had to the accompanying drawings, forming a part of the present description, illustrating a preferred embodiment of the invention, in which:

Figure 1 is a view, made on a greatly reduced scale, showing a seven-bar fence fabric, composed of marginal and intermediate strands which are connected by means of stay wires formed of short sections of stays, 75 and embodying my invention; and

Fig. 2 is an enlarged detail to illustrate the reverse bends in the strand wires and the intercoiling of the stay sections around such strands and between the reverse bends 80 thereof, the view illustrating substantially the structure enclosed within the dotted square on Fig. 1.

Like characters of reference denote corresponding parts thruout the figures.

In the drawings, reference being had particularly to Fig. 1, the top and bottom marginal or selvage wires are designated 1 and 2 and the intermediate strand wires 3. These wires are connected and spaced by 90 means of stay wires made of the short sections 4. The terminals of the top and bottom stay sections are coiled or wrapped around the top and bottom marginal or selvage wires, respectively, by the coils 5. 95 The meeting ends of the stay sections 4 where they intersect with the intermediate strands 3 are intercoiled with each other about such strands, as at 6.

As previously stated there is nothing new 100 in a fence structure made of marginal or selvage strands and intermediate strands which are connected by stay wires formed of short sections, the ends of which are coiled or intercoiled with each other about 105 such strand wires.

As very plainly shown in Fig. 2 the strand wires, and this includes all the longitudinal wires whether marginal or intermediate, are provided with reverse bends as at 7 and 8 producing short oblique portions 9 in such strand wires. It is around such oblique portions 9 of the strand wires and between the reverse bends 7 and 8 that the stay sections are coiled. On the marginal wires the terminals of the stay sections are wrapped by a single coil, whereas on the intermediate wires the meeting ends of stay sections where they intersect with the strands are intercoiled with each other about the portions 9 of the strand wires and between the reverse bends thereof, which places such intercoiled portions of the meeting stay sections, as well as the coils of the terminals of the stays at oblique angles to the perpendicular line of said stays. It is the object, as stated, to prevent slippage of the strands in the coils of the stays, or the slippage of the stays on the strands. It is obvious that with the reverse bends in the longitudinal wires and wrapping the coil portions of the stays around the strands between such bends, slippage can only occur

by the bending of the stay wires, which in practice will not occur.

The foregoing described improvement relieves a very serious objection to what is considered a very popular type of fence for farm and poultry purposes.

What I claim is:—

1. In a wire fence, in combination, a plurality of strand wires, a plurality of stay wires, the latter formed of short sections spanning the spaces between said strand wires, each strand wire where intersected by a stay section provided with reverse bends connected by a short obliquely disposed portion of strand, and each stay section having a terminal coiled about such obliquely disposed portion of a strand and between the reverse bends therein. 35

2. In a wire fence, in combination, a strand wire provided at intervals with reverse bends connected by short obliquely disposed portions, and stay sections having intercoiled ends wrapped around said strand wire between the reverse bends therein, said coils being disposed at an oblique angle to the perpendicular line of the stay sections. 40 45

WILLIAM H. SOMMER.
